REEL

Ervin E. Strawn, Passaic, N. J., assignor to Patterson Parchment Paper Company, Passaic, N. J., a corporation of New Jersey

Application October 7, 1932, Serial No. 636,658

2 Claims. (Cl. 242—119)

This invention relates to reels such as are used for supporting cords and particularly cords composed of twisted paper strips.

Twisted paper cord and vegetable parchment twisted cord such as is described in my companion application Serial No. 636,659, filed October 7, 1932, are usually made on machines of which the one known in the trade as the Watson machine is a typical example. In such a machine the paper strips are twisted into the cord formation and are wound on a large spool. From this large spool the cord is generally unwound into balls of cord whereupon the large spool is replaced in the twisting machine whenever said machine is ready for the installation of another spool. These spools are very substantial and expensive and remain in effect a part of the twisting machine. Rewinding, of course, involves machinery and labor. Under these conditions it occurred to me to investigate whether it might not be possible to create a reel of great cheapness, yet sufficiently rugged to properly position and hold the cord in place as it was manufactured by the twisting machine so that it might be possible to send the filled reel directly to the customer without any rewinding, the customer throwing away the reel when the cord has all been unwound therefrom. I have found that, within the limits imposed by the problem, it would be possible to accomplish such a result and the reel which is the result, is the subject matter of this application.

The reel is illustrated in the accompanying drawing, in which Fig. 1 is a side view partly in section; Fig. 2 is a cross section on the line 2—2 of Fig. 1; Fig. 3 is an end view of the spool; and Fig. 4 is a detail view of a modification.

In the drawing A designates two end flanges or discs of the reel composed of heavy cardboard or pressed wood, each provided with a central opening to receive and seat the metal collar B, B'. The collar B, B' is constituted of a thin strip of bendable tin or of equivalent metal said strip being bent around the end of the core C and positioned, in the finished reel, in tubular form in the apertures of each of the end discs A. The tin strip is provided with a flange portion B parallel with the exterior faces of the discs A abutting against said flanges and overlying the edges of the apertures of the said discs A, while the tubular part B' which has a minimum width which is considerably greater than the thickness of the discs A and may be greater than several thicknesses of such discs, hugs the inner periphery of the apertures of the discs A and lines the inner

periphery of said apertures. A cardboard tube or core C of appropriate thickness and length is supported in close contact with the inner periphery of the tubular metal section B' having an outside diameter approximately the same as the 60 diameter of the apertures of the discs A, so that when the parts are assembled they are all jammed tightly together. The tin sleeves B' are prick-punched or in part depressed into the body of the material constituting the core C at several 65 points as indicated at D to hold the several parts in place against axial displacement of the sleeves or outward displacement of the discs A, at least during the time that the core is wound on the reel in the twisting machine. It is preferred 70 that one of the prick-punches D shall be made at the point where as indicated in Fig. 1 the end edges of the tin sleeves B' meet or where they may slightly overlap. Instead of prick-punching the tin sleeve B' may be grooved as indicated at D' 75 in Fig. 4. The inner edge of the tubular metal section B' may also be initially bent slightly in a direction toward the tube C so as, as indicated at B'' in Fig. 4, to secure additional anchorage 80 between the sleeve B' and the tube C when the parts are finally assembled.

The first round of cord holds the tin collar in place so that it is thereafter impossible for the collar or the ends of the reel to come off the core or tube in the process of winding or of handling the reel after it has been filled. Twisted paper cord is made and wound on spools or reels at a time when the paper as such is not free from moisture, but though the paper be quite wet, the strength of the new reel is such as to maintain its 85 structure notwithstanding the strains which the presence of moisture and subsequent evaporation entails.

A twisting machine is generally provided with driving mechanism for rotating the reel at a 95 rate corresponding to the rate of formation of the twisted cord. Such mechanism contacts with the inner surface of the spool and in the case of the new reel with the inner surface of the core or tube C near the ends of the spool. 100 The prick-punching and grooving of the metal sleeve B' should therefore be limited so as not to have the metal of the sleeve pass through the tube wall so as to interfere with the proper positioning of the driving elements of the machine. When a reel such as has been described has been filled on the twisting machine it is removed therefrom and replaced by another reel of the same character. Reels so filled are shipped directly to the consumer, who, mounting them 110

upon any ordinary unwinding support, can take off and unwind the cord as and to the extent that the cord is used for its ultimate purposes. Reels such as described may, of course, be made 5 to fit any of the standard twisting machines and may be made in larger or smaller sizes appropriate to the arts in which paper cord is used. The manufacture of such reels is exceedingly 10 simple and inexpensive. The simple and inexpensive character of the reel makes it possible to market the product without rewinding and also supplies the consumer with a more convenient and attractive support for his supply of paper cord than he has thus far been able to 15 obtain.

I claim:

1. A reel for cord, comprising a heavy tubular paper core, a centrally apertured end disc at each end of the core, the walls of the apertures 20 of the discs being parallel with the outer surface of the core, and a thin pliable metallic strip intermediately situated between the wall of each disc aperture and the core having unconnected ends extending around the core in the form of 25 a sleeve, said sleeves having portions thereof depressed into the body of the core to resist axial movement of the sleeve relating to said core, said sleeves having outwardly flaring end flanges adjacent to and encircling the ends of the core, the outer circumferential surface of said sleeves being 30 parallel with the outer surface of the core and with the walls of the disc apertures, and the diameter of the disc apertures being approximately the same as the outside diameter of the 35 sleeved core so that the discs if moved from one end of the reel to the other will encounter no 40 obstruction save the end flanges, said centrally apertured end discs being positioned on said sleeves adjacent to said flanges and held in position at right angles to the axis of the core by the parallelism of the walls of the 45 apertures and the circumferential surfaces of the metal sleeves and by the abutment of the side walls of the discs against the flanges of the sleeves, each of 50 said sleeves being considerably greater in width than the thickness of the end discs and extending into the path of the cord to be wound on the reel so that the cord when wound on the core and upon the sleeves will tightly hold the sleeves in position on the core and the sleeves thus held will, in coordination with the cord wound on the reel, effectively prevent all relative 55 movement as between the core, the sleeves and the end discs, and will cause the end discs to be held on the core so that they can no longer be moved inwardly on the core or be separated therefrom during the withdrawal of cord from 60 the reel in the use of the reel.

movement as between the core, the sleeves and the end discs, and will cause the end discs to be held on the core so that they can no longer be moved inwardly on the core or be separated therefrom during the withdrawal of cord from 80 the reel in the use of the reel.

2. A reel for cord, comprising a heavy tubular paper core, a centrally apertured end disc at each end of the core, the walls of the apertures of the discs being parallel with the outer surface of the core, and a thin pliable metallic strip intermediately situated between the wall of each disc aperture and the core, having unconnected ends and extending around the core in the form of a sleeve, said sleeves having outwardly flaring end flanges adjacent to and encircling the ends of the core, the outer circumferential surface of said sleeves being parallel with the outer surface of the core and with the walls of the disc apertures and the diameter of the disc apertures being approximately the same as the outside diameter of the sleeved core so that the discs if moved from one end of the reel to the other will encounter no obstruction save the end flanges, said centrally apertured end discs being 90 positioned on said sleeves adjacent to said flanges and held in position at right angles to the axis of the core by the parallelism of the walls of the apertures and the circumferential surfaces of the metal sleeves and by the abutment of the side walls of the discs against the flanges of the sleeves, each of said sleeves being in part depressed into the material constituting the core to resist axial movement of the sleeve relatively to the core, one portion at least of said depressed 100 portions occurring at the meeting end parts of the strips of which the sleeves are formed, and each of said sleeves being considerably greater in width than the thickness of the end discs and extending into the path of the cord to be wound on the reel so that the cord when wound on the core and upon the sleeves will securely fasten the sleeves in position on the core and the sleeves thus held will, in coordination with the cord wound on the reel, effectively prevent all relative 110 movement as between the core, the sleeves and the end discs, and will cause the end discs to be held on the core so that they can no longer be moved inwardly on the core or be separated therefrom during the withdrawal of cord from 115 the reel in the use of the reel.
